UNITED STATES PATENT OFFICE

LION GARDINER, OF LAKWOOD, OHIO, ASSIGNOR TO THE JAEGER MACHINE COMPANY, OF COLUMBUS, OHIO, A CORPORATION OF OHIO

ROAD ROLLING MACHINE

Application filed March 14, 1929. Serial No. 346,939.

This invention relates to a road making machine and particularly to a machine adapted to operate on concrete, cement, or similar roads. The invention has a special utility in connection with a road finishing machine, although it is applicable to other types of road making machines as well.

In making concrete or similar roads, the material is ordinarily deposited on the road bed foundation and is then "struck off" or spread by a screed member, which member also may be adapted to give the road an approximate crowned surface. The road is usually then rolled to smooth out irregularities, eliminate air pockets or the like in the material, and to compress the material into a smooth compact mass. Since both the screed member and the roller usually are adapted to impart a crown to the road surface, these members, as well as certain other members sometimes provided upon road making machines and used in road building operations, must be either of a curvature, or must operatively move in a curved path, to impart the desired crown to the road. As the crowns which are given to different roads vary to a considerable extent in degree, a different machine must be used for forming the different degree crowns, or either the curvature of the members or their path of operative movement must be made adjustable so as to adapt the members to form the desired crown. In present practice crowns are varied by adjustment of the members themselves, or of the elements which guide the path of movement of such members, at several points by means of threaded members individually adjustable. It is a slow process and, unless adjustment is made to a template, especially cut for the purpose, any change of crown by means of individual adjustments cannot be perfectly made without individual checking at each point.

An object of this invention is to provide means in a machine of the type specified whereby any degree of crown, mathematically correct at all points, may be obtained and the necessity of rechecking after adjustment eliminated.

Another object of the invention is to provide a road making machine which has a

member adapted to impart a crown to the road surface with means for readily, quickly, accurately and easily effecting adjustments, whereby such member will be capable of imparting crowns of different degree, as desired, to the road's surface.

There have been machines with finishing members spanning a roadway which could be adjusted at a single point, usually midway of its ends, but under present-day specifications, which usually call for an accurate parabolic or similar type of crown, adjustment at a single point is not sufficient in the width of roadway now used to adjust the crown accurately to, as for example, a parabolic formula. Therefore, depending upon the width of the roadway, three, five or seven more points of adjustment may be necessary to flex a member close enough to a specified crown for practical purposes.

Hence, another object is to provide a road making machine of this character with a plurality of means controlled simultaneously from a single point for effecting such adjustments as will render the member capable of imparting crowns of different degree and particularly parabolic crowns to a roadway.

A further object is to provide a road making machine, which has a roller extending longitudinally of the roadway and adapted to operate transversely thereof to compress the material and to impart a crown thereto, with means for varying, in an expeditious manner, the curvature of the path of movement of the roller, whereby the roller may impart crowns of different degree to the road's surface.

A still further object is to provide a road making machine, which has a roller extending longitudinally of the roadway and adapted to operate transversely thereof to compress the material and to impart a crown thereto, with means for varying, in an expeditious manner, the curvature of each guide for the opposite ends of the roller, whereby the roller may impart crowns of different degree to the road's surface.

A still further object is to provide a road making machine having a roller of the character set forth, with means for varying simul-

taneously by a single controlling member and to the same extent the curvature of both of the guides supporting the ends of the roller.

Another object is to provide in a road making machine means for automatically indicating the degree of crown which the machine is adjusted to impart to the road's surface.

Another object is to provide a road making machine capable of accomplishing the above enumerated objects which is simple, easily operated and of a sturdy construction.

Additional objects and advantages will become apparent in the course of the detailed description of an embodiment of the invention which follows.

In the accompanying drawings the invention is shown, by way of illustration, as embodied in a road rolling machine, but it should be understood that in its broader aspects it could be embodied in a screed machine or in any other similar road making or finishing machines.

In the drawings:

Fig. 1 is a top plan view of the road rolling machine.

Fig. 2 is a front elevational view thereof.

Fig. 3 is a vertical sectional view taken approximately on line 3-3 of Fig. 1.

Fig. 4 is a vertical sectional view taken approximately on line 4-4 of Figs. 1 and 3.

Fig. 5 is a horizontal sectional view taken approximately on line 5-5 of Fig. 4.

Fig. 6 is a vertical sectional view taken approximately on line 6-6 of Fig. 3.

The road rolling machine comprises a frame which supports the driving and road working elements of the machine and is adapted to be moved bodily in either direction longitudinally of the roadway upon tracks 1 which constitute the usual side forms for the concrete or other material 1a. The frame includes main frame members, indicated generally in Figs. 1, 2 and 3 by the numeral 2, arranged at the front and rear of the machine and extending transversely of the roadway, such frame members being connected by members extending longitudinally of the roadway therebetween as well as by diagonally arranged members. While the main frame members may be in the form of integral channels, or in any other suitable form, they are shown herein as built-up channels, each of which is formed of a vertically arranged web plate 3, as shown in Figs. 4, 5 and 6, which plate extends entirely across the machines and has inwardly and oppositely facing angle bars 4 secured to it by suitable means adjacent its upper and lower edges. The connecting members between the main frame members include channels 5 secured by suitable means, such as gusset plates 6, 7, 8, and 9 to the main frame members intermediate the ends of such mem-

bers and adjacent to their upper edge. There are four of these frame members 5 shown in the drawings but, of course, it should be understood that any desirable number thereof might be used, the two outer members being connected to the two inner members by diagonal frame members 10 secured to the gusset plates 6 and 9.

At the front of the machine a frame member 11 parallel with the main frame member 2 but spaced inwardly thereof, extends between the two inner frame members 5 and is connected to the gusset plates 9, while at the rear end of the machine the frame members 12 and 13 are similarly arranged and are connected to the gusset plates 8. This last described arrangement provides a support for the platform which carries the driving mechanism for the machine as well as providing supports for the bearings of some of the operative parts of the machine.

As already stated, the machine is adapted to move in either direction longitudinally of the roadway and for the purpose of effecting such movement, as well as for the purpose of effecting the operation of the roller, a suitable motor or other source of power 14 is arranged on the frame adjacent the front of the machine, which motor is connected through a change speed gearing 15 controlled by a lever 16 to shafts 17 and 18, the first of which is provided with a clutch 19 controlled by a lever 20 and the second of which is also provided with a clutch controlled by the lever 21. The shaft 17 is arranged at the front of the machine beyond the main frame member 2 being supported in forwardly extending brackets 22 secured to the web plate 3 of the frame member by angle brackets 23. The shaft 17 is provided with a plurality of driving connections 24, for a purpose well understood and carries upon each opposite end a wheel 25 which travels upon the tracks or forms 1. At the rear of the machine, supporting brackets 26, similar to the brackets 22, are secured to the web plate 3 of the main frame member and extend rearwardly therefrom, such brackets supporting short shafts 27 which carry at their outer ends, wheels 28, also engaging the tracks or forms 1 and traveling thereon.

The driving mechanism of the machine not forming a part of the invention in its specific details, it should be sufficient to say that the machine may be moved in either direction longitudinally of the road upon the tracks or forms 1 by manipulating the control levers 16 and 20 so as to provide for the actuation of the shaft 17 in the proper direction and speed and, in turn, to provide for the drive of the wheels 25 carried by the shaft.

The roller 29 extends between the main frame members 2 and is adapted to be moved in either direction transversely of the road.

While the roller 29 may be of any desired and suitable construction, it is shown herein as comprising a relatively large metallic cylinder provided at its opposite ends with spindles 30 upon the end of which spindles are arranged guide rollers 31. These guide rollers travel in inwardly facing channels 32 adjustably secured to each of the main frame members 2. In providing for this adjustable 10 securing of the channels 32 to the main frame members 2, such members are provided upon their inner sides with a plurality of spaced vertically extending slotted T-guides 33 within the slot of which slidably 15 engages a T-head 34 carried by members 35 which are secured to the back of the web of the channels 32. As shown, there are five of these T-shaped guide members secured to each main frame member, the two outer guide 20 members being arranged adjacent the outer ends of the frame member and the innermost of the guide members being arranged approximately at the middle of the frame members, the other two guides being arranged 25 intermediate the middle guide and the two outer guides respectively. It is, of course, understood that the guides on each frame member align with the corresponding guides 30 on the other frame member so that uniform adjustment of the two channels 32 will be possible.

The members 35 extend upwardly above the top of the channels 32 and inwardly over the top thereof and have at their upper ends 35 an enlarged cylindrical portion 36 which fits between the arms of a yoke 37 carried by a threaded sleeve 38 and is held in the yoke by a pin 39. Each of the threaded sleeves 38 receive bolts 40, which bolts extend upwardly through the angles 4 of the main frame members 2 and through threaded bearing members 41 carried by the upper side of the main frame members. The two outermost bolts 40 on each frame member are 45 provided with a squared head or other suitable wrench-receiving means 42 so that they may be adjustably positioned in their respective bearings 41. These bolts are also provided on their upper end with suitable lock nuts 43 so that they may be maintained in their position of adjustment.

The three intermediate bolts on each of the main frame members is provided on its upper end with a bevel gear 45, each of said 55 gears cooperating with a pinion 46 arranged on shafts 47 and 48 mounted, respectively, at the rear and front of the machine in bearing supports carried by the main frame members. The shaft 49 mounted in suitable 60 bearings arranged upon the platform portion of the machine extends between the two shafts 47 and 48 and carries at its opposite ends pinions 50 which mesh with pinions 51 carried by the shafts 47 and 48. At the front 65 of the machine upon the platform portion a

vertically extending supporting frame 52 is arranged, which frame is provided adjacent its upper end with a bearing supporting a short shaft 53 which carries on its forward end a sprocket 54 and on its inner end a hand wheel 55, the sprocket 54 being connected by a sprocket chain 56 to a sprocket 57 keyed on the shaft 49. It will thus be obvious that when the hand wheel 55 is rotated that the shaft 49 will also be rotated and, in turn, the shafts 47 and 48. The rotation of these last-named shafts will, of course, rotate the bolts 40 in their threaded bearings through the pinions 46 and gears 45 and will cause the sleeves 38 secured on the bolts to be raised or lowered and, in turn, tend to pull up or push down the channel 32. Since the movement of the bolts 40 must vary according to its relative position with respect to the channel 32 so that the proper degree of curvature may be imparted to said channel, the threads of such bolts will, of course, be of different pitch in accordance with the position in which the bolt is to be used. It might be well to state at this time that instead of using bolts of different thread pitch that the same result could be obtained by using different gear ratios.

In order to move the roller 29 backwardly and forwardly transversely of the roadway, the roller is provided with an operative connection to the shaft 18 which, as previously set forth, is driven by the motor 14. The shaft 18 carries a sprocket 58 on each end thereof while an automatic reversing mechanism 59 is arranged intermediate the ends of the shaft 18, it having already been stated that the shaft 18 is provided with a clutch mechanism operable by the lever 21. A pair of small sprockets 60 is carried by each main frame member below and to one side of the sprocket 58, while sprockets 61 are arranged at each end of each main frame member at a point just above the ends of the channels 32.

Extending over the sprockets 58, 60 and 61 is a drive chain 62 which has its free ends connected to hooks 63 secured to a two-part bracket member 64 arranged on each of the roller spindles 30 intermediate the guide roller 31 and the end of the roller 29. It will thus be seen that when the shaft 18 is rotating in one direction that each of the chains 62 will be moved by its sprocket 58 and that the roller 29 will be pulled by the chain and moved with its guide rollers 31 riding in the channels 32. The automatic reversing mechanism 59 is so adjusted as to automatically reverse the rotation of the shaft 18 when the roller 29 reaches its limit of movement in either direction. Thus so long as the clutch for the shaft 18 is in the operating position, the roller 29 will continue to move backwardly and forwardly transversely of the road 120 125 130

and to compress the material of which the road is formed.

A sleeve 65 extends upwardly from the platform adjacent the rear of the machine 5 and carries at its upper end an indicating dial 66 graduated to show different degrees of crowns. A flexible shaft 67 is pivotally connected at its lower end to the adjacent sleeve 38 and at its upper end is operatively 10 connected to an indicating arm 68 rotatably supported in front of the face of the dial 66, so that when the sleeve 38 is moved in either direction the indicating arm 68 will also be moved across the face of the dial by the 15 shaft 67. The graduations upon the dial may be based upon a fixed setting at the ends of the trackway with the result that the deflection of the middle point of the trackway above the horizontal line between the two 20 ends thereof will correspond to the crest of the crown and may be expressed in any desired units, such as inches.

In adjusting the curvature of the channels 32 so that the path of movement of the 25 roller 29 will be such as to form the desired crown upon the road, the bolts 40 at each end of each channel are turned by means of a wrench or other suitable tool applied to the 30 ends 42 of the end bolts until the ends of the channels are properly positioned to enable the roller to engage the road at the level of the forms 1 when it is at each end of its reciprocation transversely of the road. The 35 bolts 40 may then be locked in such position 40 of adjustment by means of the lock nuts or similar means 43. The hand wheel 55 is then turned by the operator with the result that rotation of the shaft 49 through its operative connection with the shafts 47 and 48 will rotate the latter shafts and, in turn, the intermediate bolts 40 through the bevel gears 45 and pinions 46. This rotation of the intermediate bolts 40 will, according to their direction of rotation, either raise the intermediate 45 portion of the channels 32 or will tend to depress the same. The action of the bolts upon the channels, which are fixed at their opposite ends, is such that the channels will be flexed into the proper curvature for imparting 50 a curved path of movement to the roller to enable it to form the desired crown on the road. The operator will be able to tell from the indicating dial 66 when the proper curvature has been given to the channels. 55 It will be seen that the channels 32 are free to slide vertically on the web plates 3 of the main frame members 2 since they are secured thereto by the T-heads 34 sliding in guideways 33, while they are held by the same 60 means against movement laterally of the frame members. Once the end plates have been adjusted, the operator simply needs to turn the hand wheel 55 in the desired direction and in the desired amount to procure 65 adjustment for the crown which is to be

imparted to the road. As soon as the necessary crown adjustment has been procured the operating mechanism for the roller is set into action and the roller in its transverse reciprocation of the roadway will compress the material and form the desired crown on the roadway. 70

While one embodiment of the invention has been illustrated and described herein, it should be distinctly understood that the same is not to be limited thereto but is susceptible of embodiment in various types of road making machines and with various members of such machines within the scope of the appended claims. 75

Having thus described my invention, I claim:

1. In a machine of the character described, road engaging means adapted to impart a crown to the road, a plurality of adjustable means for causing said first-named means to impart crowns of different degree to the road, and a single means for operating said second-named means. 85

2. In a machine of the character described, road engaging means adapted to impart a crown to the road, a plurality of adjustable means for causing said first-named means to impart crowns of different degree to the road, and means for simultaneously operating said 95 second-named means.

3. In a machine of the character described, a road engaging member reciprocable transversely of the roadway and adapted to impart a crown surface thereto, adjustable means for causing said member to impart crown surfaces of different degree to the road, and means for simultaneously operating said last-named means from a single operating station. 100

4. In a machine of the character described, a road engaging member reciprocable transversely of the roadway and adapted to impart a crown surface thereto, means including a plurality of adjustable members for causing said road engaging member to impart crown surfaces of different degree to the road, and means for simultaneously operating said adjustable members. 110

5. In a machine of the character described, a road engaging member reciprocable transversely of the roadway and adapted to impart a crown surface thereto, means including a plurality of adjustable members for causing said road engaging member to impart crown surfaces of different degree to the road, and a single means for simultaneously operating said adjustable members. 115

6. In a machine of the character described, a road engaging member reciprocable transversely of the roadway and adapted to impart a crown surface thereto, means including a plurality of adjustable members for causing said road engaging member to impart 125

- crown surfaces of different degree to the road, and a common means having an operative connection with said adjustable members for simultaneously operating said members.
5. 7. In a machine of the character described, a frame adapted to move longitudinally of the roadway, a road engaging member reciprocable transversely of the roadway and supported by said frame and adapted to impart a crown surface to the road, means for causing said member to impart crown surfaces of different degree to the road, and means operable from a single point on said frame for operating said last-named means.
10. 8. In a machine of the character described, a frame adapted to move longitudinally of the roadway, a roller reciprocable transversely of the roadway and adapted to impart a crown surface thereto, means on said frame for guiding the path of movement of said roller, and means operable from a single point on the frame for changing said last-named means to change the path of movement of the roller to impart different crowns to the roadway.
15. 9. In a machine of the character described, a frame, a surfacing member reciprocable transversely of the roadway and adapted to impart a crown surface thereto, means on said frame for supporting said member and for determining the path of movement of the same, means for changing the shape of said last-named means to alter the path of movement of the member, and means for operating said second-named means from a single point on the frame.
20. 10. In a machine of the character described, a frame, a surfacing member reciprocable transversely of the roadway and adapted to impart a crown surface thereto, means carried by the frame and extending transversely of the roadway for supporting the opposite ends of said member and determining the path of movement thereof, means for adjusting each of said last-named means to vary the curvature thereof, and means for simultaneously operating each of said second-named means.
25. 11. In a machine of the character described, a frame, a member arranged at each end of the frame and extending transversely of the roadway, a roller extending between said members and having its opposite ends movably supported thereby to reciprocate transversely of the roadway and impart a crown thereto, means for flexing said members to change the curvature thereof to enable said roller to impart crowns of different degree, and means for operating said last-named means to simultaneously and uniformly change the curvature of said members.
30. 12. In a machine of the character described, a frame, a pair of laterally spaced members supported by said frame and extending transversely of the roadway, a roller extending between said members and supported thereby to reciprocate transversely of the roadway and to impart a crown thereto, a plurality of adjustable members connected to each of said first-named members and adapted to change the curvature thereof, and a common operating means for the said adjustable members.
35. 13. In a machine of the character described, a frame, a pair of members adjustably supported thereby, one of said members being arranged at one end of the frame and the other at the opposite end of the frame, a roller extending between said members and supported thereby and adapted to reciprocate transversely of the roadway to impart a crown surface thereto, means for changing the curvature of said members, and a common means for operating said last-named means.
40. 14. In a machine of the character described, a frame, a guide member arranged at each end of the frame and vertically movable thereon, means for adjusting in fixed position the opposite ends of said guide members, means intermediate the ends of said guide members for flexing the same to different curvatures, and a single means for operating said last-named means and simultaneously flexing both of said guide members.
45. 15. In a machine of the character described, a frame, a pair of members spaced laterally of each other and extending transversely of the roadway, a roller extending between said members and having its opposite ends movably supported thereby to reciprocate transversely of the roadway and impart a crown surface thereto, means for changing the curvature of each of said members to enable said roller to impart crowns of different degree, and means for operating each of said last-named means from a single point on the frame.
50. 16. In a machine of the character described, a frame, a guide member arranged on said frame and vertically movable thereon, means for adjusting in fixed position the opposite ends of said guide member, means intermediate the ends of said guide member for flexing the same to different curvatures, and a common means for operating said last-named means.
55. 17. In a machine of the character described, a frame, a pair of channel members arranged on said frame and extending transversely of the road, means for adjusting the opposite ends of each of said channel members and for holding the same in adjusted position, a plurality of means intermediate the ends of each of the channel members for flexing the same and changing the curvature thereof, and means for simultaneously operating said flexing means.
60. 18. In a machine of the character described,

scribed, a frame, a pair of spaced channel members slidably arranged on said frame but held against lateral movement, means for holding the opposite ends of said channel members in various fixed positions of adjustment, means intermediate the ends of said channel members for adjustably raising or lowering the same to cause a flexure thereof, and means simultaneously and uniformly 10 flexing said channel members.

19. In a machine of the character described, a frame, a pair of spaced members carried thereby, a plurality of threaded bolts connected to each of said members and rotatable in threaded bearings on the frame, means for adjusting the bolts adjacent each end of the said members and locking the same in adjusted position, gears arranged on the ends of each of the bolts intermediate the 15 end bolts, a shaft adjacent each member provided with a plurality of gears cooperating with the gears on the bolts, and a common means for rotating both of said shafts to simultaneously rotate said intermediate bolts 20 to flex said members to change the curvature 25 thereof.

20. In a machine of the character described, a frame, a guide member arranged on said frame and vertically movable thereon, means for adjusting in fixed position the opposite ends of said guide member, a plurality of means intermediate the ends of said guide member for flexing the same to different curvatures, a common means for operating 30 said last-named means, and an indicating device associated with one of said flexing means to indicate the degree of curvature of said guide member.

In testimony whereof, I hereunto affix my 35 signature.

LION GARDINER.
